UNITED STATES PATENT OFFICE.

STANLEY W. HAYES, OF RICHMOND, INDIANA.

DERRAIL.

1,176,289.

Specification of Letters Patent. Patented Mar. 21, 1916.

Application filed September 5, 1914. Serial No. 860,355.

To all whom it may concern:

Be it known that I, STANLEY W. HAYES, a citizen of the United States, residing at Richmond, in the county of Wayne, State 5 of Indiana, have invented the following described Improvements in Derails.

The improvement involves certain principles of construction and operation capable of application to derails in various ways 10 to improve the utility thereof, and includes a method and means of assembling and relating the several parts of derails whereby they can be operated by hand or by foot in one or both directions, and whereby they 15 may be readily and automatically latched and locked in one or both positions, and whereby the character of movement of the derail block toward and from the rail may be made to suit various requirements, 20 whether operated by foot or otherwise, and also certain other features of advantage and improvement, all as hereinafter set forth and claimed.

In the drawings, Figures 1 and 2 are top 25 plans of one form of this invention, illustrating the features above referred to, Fig. 1 showing the derail open and Fig. 2 closed; Fig. 3 is a longitudinal section of the closed derail, with parts in elevation; Fig. 4 a 30 rear view of the same in the open position; Fig. 5 a side elevation of the open derail; Fig. 6 a section at the latch, the derail being open; and Fig. 7 the same with the 35 derail closed.

The derail comprises a base with flanges 1 on either side, by means of which it may be spiked to two adjacent ties. Such portion of the base as depends below the flanges occupies the space between the ties, and the 40 forward or rail end of the base turns upwardly so as to abut against the web of the rail when in proper position on the road-bed. The upright side wall portions 2 are joined by a roof 3 and braced and reinforced by a couple of angle ribs 4 as 45 well as by a rear wall 5. The base structure is desirably made or cast in a single piece, although it might be otherwise, and within its interior are formed the various 50 bearing surfaces by which the moving derailing member is supported and guided. The derailing member is preferably also, but not necessarily, a single piece or casting, and comprises a derail-block 6 carried 55 at the forward end of the main or body portion, which latter is confined within the

base and provided with a set of bearing surfaces complementary to and adapted to cooperate with the bearing surfaces on the base above referred to.

As indicated in the drawings, and particularly in Figs. 6 and 7, the main body of the derailing member is hollow on its under side, being cast or formed of side wall and roof portions, suitably rib-braced 60 in the interior, and its forward portion, marked 7, is considerably wider than its rear or tail portion, marked 8. The wider part substantially fills the space between the side walls 2 of the derail, while the 65 narrow tail portion 8 is adapted to be guided in and project through the relatively small opening in the rear wall 5. Moreover the wide and narrow parts of the derailing member are disposed at an angle 70 to each other and at about their point of junction, that is to say, in the region of the apex of the angle, the said member has its forward bearings. In the present 75 case, this bearing consists of a pair of opposite studs 9, each normally resting on a bearing surface 10 on the base and adapted also to engage an upper inclined bearing surface 11 immediately above the said surface 10. The two surfaces 10 and 11 80 constitute the horizontal walls of a curved groove formed in each side wall of the base or standard, and are open at their forward end to permit the introduction of the studs 85 therein, the rear end of the grooves being 90 open downwardly through a hole 12, this latter hole serving to make the grooves self-cleaning of dirt.

The derailing member is adapted to tilt or rock on the bearing studs 9 within the 95 limits prescribed by the arrangement of the other parts, and also and coincidently to slide in the groove toward or from the derail, the curvature of the said groove serving to impart a curvilinear direction, or up-and-over component, to the path of movement of the derailing member as a whole. Such curvature may be greater or less, as desired and as will be evident, and according to the disposition of the grooves. At its 100 rear end the derailing member is adapted to be supported alternately on the lower and upper margins of the opening in the rear wall 5. The lower surface of said opening, marked 13 (Fig. 3) is adapted to be engaged 105 by the under surface 14 of the body part 8, that is to say, by the bottom edges of the 110

side wall of the derailing member, and the said surface 13 also serves as a fulcrum bearing, for which the body of the derailing member is the lever. When acting as such fulcrum bearing, vertical or downward pressure on the projecting rear end of the derailing member will force the studs 9 upwardly against the surface 11 above described, and by virtue of the inclination or curvature of that surface will cause the studs to move forwardly in their grooves, thereby moving the derail block toward the rail. Such movement takes place in a gradual upward direction which continues until near the end of the stroke, when, by virtue of the decreasing leverage and the change of direction of the grooves or surface 11, the derail block 6 drops upon the rail, assuming the position indicated in Fig. 5. In this position the shoulder portions 15 depending below the derail block, occupy the thrust-seat formed by the space between the extended side walls 2 at the rail end of the standard, dropping into such seat from the top of their path of movement. The thrust-seat serves to prevent movement of the derail block longitudinally of the rail. The shoulders 15 are constituted by the side walls of the body part 7, and are rounded, as indicated, so that they may, if desired, ride on the complementary base shoulders 16 when moving into the seat. These base shoulders 16 project inwardly from the side walls 2 far enough to accommodate the support of the shoulders 15, but so as to leave an open space between them (see Fig. 2), through which foreign objects may pass through the base without remaining to obstruct operation of the device. The perforated lug 31 between and slightly forward of the bearing studs 9 is a connection lug formed as a downward extension of one of the internal bracing-ribs in the interior of the body part 7. The derail may be connected with a pipeline or target-stand by means of this lug, if such connection is desired.

The upper surface 17 of the rear opening in the base structure is adapted to be engaged by the upper edge of a fin 18, extending from a point near the studs 9 to a point near the end of the derailing member, and the function of such engagement is to limit and control the extent of downward tilting of the derail block end of the member, this end being, of course, much heavier than the narrow tail end. The shape of the fin may obviously be made to permit greater or less tilting movement, although it will be evident that a change of the angle between the body parts 7 and 8 can also be resorted to for controlling the tilting action.

With the derail in the open position of Fig. 5, a wedge or cam surface 19 formed on the under side of the tail end of the derailing member is directly over a corre-

sponding wedge surface or cam 20 on the base, and by tilting the rear end of the member downwardly, as by pressing upon it with the foot, the said surfaces may be brought into engagement, and such engagement will draw or force the derail block from the rail sufficiently to start it over the incline 21 of the groove (Fig. 3) or over the incline of the base shoulders 16, as the case may be, and thereupon gravity impels the member the rest of the way back to its closed position. During such movement, the rear end of the derailing member rises corresponding to the depression of the derail-block. 70 75 80

From the foregoing it will be evident that the arrangement of bearing surfaces between the derailing member and its structure coöperate to impart movement of the former transversely of the rail and in either direction, and that both such movements are or may be the result of pressure or force applied, in both instances, in a vertical direction or a direction transverse to the movement toward the rail. The device may thus be readily operated by the foot, as by stepping upon the foot-hold 22 provided for the purpose. It may also be operated by hand, if desired, and for this purpose the hand-hole 23 is formed in the roof wall of the hollow body part 7. When thus operated the upward pull on the forward end results in the same effect as downward pressure on the rear end; and inasmuch as it is natural to pull upwardly when performing the manual operation, the block moves with so much the greater facility. Either method of operation may thus be used and one or more combinations of co-operating surfaces may be employed to provide one or more of the movements described, it being evident that the retractive surfaces operate independently of the advancing surfaces and that either may hence be used to the exclusion of the other. The rear end of the derailing member moves downwardly in the beginning of the stroke in each direction and the derail may thus be locked closed or open by means of a latch 24 adapted to obstruct such downward movement. The latch 24 is pivoted in a frame 25 forming part of the base structure and is adapted to swing by the effect of gravity under the rear part 8. In the open position it hooks under the extreme rear end, and in the closed position under the ledge 26 formed by a recess cast in the side wall. In intermediate positions it is held from swinging into locking position by the engagement of its nose with the side of the derailing member. Additional means are provided to hold the latch withdrawn, even at the ends of the stroke, so that it can be first withdrawn to remain in that position while the operating force is being 110 115 120 125 130

5 applied to the foot or hand hold, thereby providing but one part to be operated at a time. To this end the latch 24 is loosely pivoted at its pin in the frame 25 and its hub carries a spur 27. By raising the latch, which may be done with the foot or hand, the spur is caused to ride over either one of two corresponding spurs 28, 29 according as the derail is in one position or the other. These spurs are formed on the 10 back of the derailing member and hold the latch in its withdrawn position until movement of the derailing member withdraws the spurs, whereupon the nose of the latch 15 will then rest against and ride over the side of the derailing member ready to hook under the same again at the end of the stroke. The latch has a handle 30 by which it is readily engaged by the hand or foot and 20 directly above the handle, when the latch is in its locking position, a hole 32 is drilled through the corner of the rib 4 so that a padlock looped therein will lock the latch and derail in either closed or open 25 position.

30 From the foregoing, it will be evident to those skilled in this art that the device described is susceptible of various modifications and change in the proportions of its parts, and it will be understood that the 35 following claims are intended to cover all such modifications, changes and also reversals of arrangement within the scope of the invention, the principles of which have now been clearly set forth.

I claim:

1. A derail comprising a derailing member, a base supporting and guiding the same and complementary bearing surfaces on said 40 member and base adapted to coöperate to force the member toward or from the rail as the result of force applied to the member transversely of the direction of such movement.

45 2. A derail comprising a base having a slideway therein, a derailing member having a rocking bearing engaging the slideway and movable therein toward and from the rail, and wedge surfaces formed on the base 50 and member adapted by engagement to impart movement to the derailing member transversely of the rail.

55 3. A derail comprising a base, a derailing member mounted thereon to move toward and from the rail and complementary surfaces formed on the base and member, respectively adapted to be forced into engagement and by a camming action to impart movement to the member transversely of the 60 rail.

65 4. A derail comprising a base, a derailing member movably mounted thereon and complementary engaging surfaces between said base and member, one of such surfaces forming a fulcrum, as to which the said member

is the lever, and another of such surfaces being inclined relatively to the lever motion of the member and adapted for engagement therewith to move said member transversely of the rail.

5. A derail comprising a base, a derailing member movably mounted thereon and co-acting surfaces formed on these parts, one of such surfaces being a fulcrum bearing upon which the derailing member is the lever, and adapted to slide thereon, and another of such surfaces being inclined and adapted to be engaged by the lever derailing member to cause it to move transversely of the rail.

70 6. A derail comprising a base, a lever derailing member slidingly fulcrumed on the base, and pairs of co-acting surfaces on the derailing member and base adapted, respectively, to cam the derailing member toward 75 and from the rail upon force being applied to the derailing member in a general vertical direction.

80 7. A derail comprising a base, a derailing member mounted therein and provided with 85 a rear portion projecting beyond the rear of the base and co-acting inclined surfaces formed on such parts whereby pressure in a vertical direction on the projecting end starts the derailing member in motion.

85 8. A derail comprising a derailing member having a head and a body part, of which the head and tail portions are disposed at an angle to each other, the base having a slide-way, and a rocking bearing on the derailing member engaging said slideway, the 90 said bearing being disposed at the junction of the said head and tail portions of the body.

95 9. A derail comprising a derailing member having its head and tail portions disposed at an angle to each other and adapted to tilt or rock on an axis in the region of the apex of such angle, a base supporting and guiding the member, and wedge surfaces 100 formed respectively on the base and member adapted to be engaged by the tilting thereof to start the member in motion.

105 10. In a derail, a derailing member comprising a body portion having a derailing head thereon, said body being wide adjacent the head and narrow at its opposite end and having bearings adapting it to rock or tilt on an axis adjacent the junction of the wide and narrow portions of said body, in combination with means whereby the rocking of said member slides the same toward or from the rail.

110 11. A derail comprising a base, a derailing member supported and guided thereon for sliding movement transversely of the rail and a latch automatically moving to locked position with reference to said member.

115 12. A derail comprising a base, a derail-

- ing member supported and guided therein with its rear end adapted to project beyond the base and a latch applied to the rear of the base and adapted to return automatically 5 to the position in which it locks the derailing member against movement.
13. A derail comprising a base, a derailing member supported and guided therein and a latch for said member normally urged 10 to position to lock the member against movement, and means whereby such latch becomes operative only at the end of the stroke.
14. A derail comprising a base, a derailing member supported and guided therein and 15 a latch mounted on the base for locking the member against movement, said latch being held in inactive position by the derailing member during movement of the same.
15. A derail comprising a base and a 20 moving derailing member, combined with a gravity actuated latch for locking the member against movement and means positioned by the member for temporarily sustaining the latch against gravity at the beginning 25 of the stroke of the member.
16. A derail comprising a base, a derailing member supported and guided thereon, a latch normally urged to locking position with reference to said member, and means 30 whereby the latch can be padlocked in its said locking position.
17. A derail comprising a base, a derailing member supported and guided thereon and a latch normally urged to locking position 35 with reference to the movement of said member, means for holding the latch ineffective throughout the intermediate portion of the stroke of said member, and independent means for temporarily withholding the latch 40 at the beginning of the stroke.
18. A derail comprising a base, a derailing member thereon and a latch adapted to lock the derailing member and arranged to fall by gravity into its locking position, in 45 combination with coöperating shoulders on the latch and member whereby the former is held out of locking position.
19. A derail comprising a base, a derailing member having a rocking bearing on the 50 base upon which it may slide toward and from the rail and a bearing on the top of said member adapted to engage the top of the base to limit the downward movement of the head of the derail.
- 55 20. A derail comprising a base, a derailing member having the rear portion projecting beyond the base and bearing surfaces respectively on said parts whereby the said projecting end moves downwardly in the beginning of the stroke of the derail in each direction.
21. A derail comprising a base and a derailing member, the latter supported on the former by surfaces which produce a rocking motion of the derailing member and a latch 65 adapted to obstruct such rocking motion and thereby prevent movement of the derailing member transversely of the rail.
22. A derail comprising a base, a lever derailing member slidingly fulcrumed on the 70 base, and guiding means on the base coöperating with the derailing member to conduct the latter to position upon the rail upon the application of foot pressure to the tail of the member. 75
23. A derail comprising a base, a derailing member tiltingly and slidingly mounted on the base, means on the base affording an elevation over which the forward portion of the derail must be raised in order to remove 80 it from the rail, and co-acting surfaces on the base and member adapted to draw said forward portion over such elevation upon downward pressure being applied to the tail of the derailing member when the latter is 85 in open position.
24. A derail comprising a base having curved or inclined guide means, a derailing member having sliding and rocking engagement in said guide means and provided with 90 a tail adapted to be depressed by foot pressure, and means comprising surfaces on the base and member operative when the member is in open position and its tail portion is depressed to force the said member away 95 from the rail to a point where it slides by gravity down the guide means.
25. A derail comprising a base having curved or inclined guide grooves, and a derailing member provided with a pair of 100 opposite studs having sliding and rocking engagement with said grooves and also provided with a tail adapted to be depressed by foot pressure to cause said studs to traverse said grooves. 105
26. A derail comprising a base having curved or inclined guide means, a lever derailing member having sliding and rocking engagement therewith and provided with a tail adapted to be depressed by foot pressure, and a fulcrum on the base for sliding engagement by the derailing member, the said guide means being between the fulcrum and the rail.

In testimony whereof I have signed this 115 specification in the presence of two witnesses.

STANLEY W. HAYES.
